Patented Jan. 16, 1968

209,921

SPRING WINDING MACHINE

Erman V. Cavagnero, Torrington, Conn., Wilbur L. Sheffield, Westwood, Mass., and Joseph L. Morro, Torrington, Conn., assignors to The Torrington Manufacturing Company, Torrington, Conn., a corporation of Connecticut

Filed Oct. 10, 1966, Ser. No. 4,211

Term of patent 14 years

(Cl. D55—1)

FIGURE 1

FIG. 3

Des. 209,921

PAGE 4

FIG. 1 is a top view of the spring winding machine showing our new design;

FIG. 2 is a left-hand side elevational view of the spring winding machine;

FIG. 3 is a front elevational view thereof;

FIG. 4 is a right-hand side elevational view thereof;

FIG. 5 is a rear elevational view thereof; and

FIG. 6 is a perspective view of the spring winding machine.

We claim:

The ornamental design for a spring winding machine, as shown.
